SIGNORS TO WAYNE COMPANY, OF FORT WAYNE, INDIANA, A CORPORATION OF
INDIANA.

DISCHARGE VALVE FOR ICE-MACHINE COMPRESSORS.

Application filed July 11, 1927. Serial No. 204,780.

Our invention relates to discharge valves for the compressors of ice machines and particularly to those for domestic use. Such valves must operate at high speed. On the 5 best form of our apparatus now known to us this valve normally opens approximately three hundred and ten times a minute. The extent to which the valve opens is very slight. Ordinarily the refrigerant in 10 gaseous form only passes the valve, but occasionally a slug of liquid refrigerant passes through and the valve must be constructed so as to operate efficiently under all conditions without damage to itself.

15 Our invention is adapted to meet such needs and consists essentially of an ordinary plain valve seat with a flexible plate valve slidably confined at its ends and when unflexed resting on the valve seat and spaced 20 above said valve a flexible stop also slidably confined at its ends. Between the valve plate and stop element is maintained a film of lubricant.

The principal object of our invention is to 25 provide a plate discharge valve held but not clamped at the ends so that said ends are free to slide when said valve is flexed by pressure upon the middle portion; distributing the strain.

30 Another object of our invention is to provide a plate discharge valve capable of being flexed sufficiently to allow charges of gas to pass the valve, and backed up by a flexible stop element capable of being flexed along 35 with the valve to allow slugs of liquid to pass.

We prefer to use no valve cap or positive stop.

The film of oil between the valve and stop 40 not only lubricates the device but acts as a cushion giving the device a dash-pot effect, relieving the moving parts of undue tension that might otherwise tend to destroy or reduce their resiliency.

45 In the particular embodiment of our invention selected for illustration:—

Figure 1, is the top part of an electrical- 50 ly driven ice machine compressor cylinder and head, in vertical axial section,

Fig. 2, is a top plan view of the same as though shown there in full but with the cylinder head removed,

Fig. 3, is a detail of the plate valve,

Fig. 4, is an enlarged detail of one of the 55 spacers,

Fig. 5, an enlarged detail, is a side elevation of one of the washers, and

Fig. 6, a detail, is a vertical axial section of the valve and attendant parts, when the valve is open, the degree of its lifting being exaggerated for the sake of better illustrating the position it takes.

Referring now to the drawings A is the compressor cylinder, A¹ the valve plate and A² the cylinder head; A¹ and A² being secured in position on the top end of the cylinder A by cap screws s. A port a is formed through the plate A¹ and contiguous thereto is the valve seat a¹.

The valve B is a resilient plate with a hole b at each end, and these holes are made large enough to allow lengthwise movement of the valve when flexed. On top of the plate valve B, at each end is placed a spacer C with a hole c similar to the holes b, and locking 75 lugs c¹, c¹. Ordinarily we prefer to make these spacers approximately four-one-thousandths of an inch thick.

A flexible stop member D, is a plate similar in all respects to the valve B, except it is preferably thicker and rests upon the spacers C at each end spacing it above said valve. The locking lugs c¹, c¹ are bent around and over the edges of the stop D and 80 secure the spacer C to the stop D.

The valve plate A¹ is bored and tapped at a², a² to receive the screws s¹, s¹. A washer W is provided for each of the screws s¹. The tubular portion w is of such size as to fit loosely in the holes b of the plate valve B, the holes c of the spacer C and the similar holes of the stop D; and is of such length as when the screw s¹ is tightened down it will hold the valve, spacer and stop securely in position but so as to allow the valve B to slide longitudinally at its ends when it is bent upwardly upon the passage of gaseous refrigerant from the cylinder A; or so as to allow for sliding movement of both valve B and stop D at the ends when liquid refrigerant passes from the cylinder A.

Many changes may be made in the design here shown without departing from the spirit of our invention, and it is our intention to claim all designs involving a plate

valve, with or without a co-acting flexible stop, held down at the ends but without clamping so that when pressure under the valve at a point between the ends by the fluid seeking to escape flexes the valve, it will be free to slide at its ends.

We claim as our invention and desire to secure by Letters Patent of the United States:—

- 10 1. In a relief valve mechanism a resilient plate valve whose mid-portion covers the port, superimposed means adapted to progressively conform to the shape of said valve as flexed for limiting the flex of said valve
- 15 2. and means for holding said valve down at both ends but without clamping it so as to permit said valve to make sliding adjustment longitudinally at the ends when said valve is flexed.
- 20 3. In a relief valve mechanism a resilient plate valve whose mid-portion covers the port, an opening through said valve plate at each end thereof, means co-acting with said valve at said openings for holding said valve
- 25 down at the ends but without clamping it so as to permit said valve to make sliding longitudinal adjustment at the ends when said valve is flexed and superimposed means limiting the flex of said valve.
- 30 4. A relief valve mechanism comprising a valve plate, a port through said plate, a valve seat adjacent said port, a resilient plate valve adapted to rest on and close said port and superimposed means limiting the flex
- 35 of said resilient plate valve, an opening through said valve at each end thereof, and means co-operating with said valve at said openings for snugly but slidably holding said valve in position.
- 40 5. In a relief valve mechanism a resilient plate valve whose mid-portion covers the port, a resilient stop plate above the valve, means at each end for spacing said stop from the valve and common means for holding
- 45 both valve and stop snugly in place at the ends without clamping them, so as to permit them to make sliding adjustment longitudinally at the ends when flexed.
- 50 6. A relief valve mechanism comprising a valve plate, a port through said plate, a valve seat adjacent said port, a resilient plate valve adapted to rest on and close said port, an opening through said valve at each end thereof, a resilient plate stop, an opening
- 55 through said stop at each end thereof,

the openings through said valve and through said stop adapted to register, means for spacing the stop from the valve and means extending through said openings for snugly but slidably holding said valve and stop in 60 position.

6. A relief valve mechanism comprising a valve plate, a port through said plate, a valve seat adjacent said port, a resilient plate valve adapted to rest on and close said 65 port, a hole through each end of said valve, a resilient plate stop, a hole through each end of said stop, said valve holes and stop holes registering, means for spacing the stop from the valve, and means extending 70 through said holes for snugly but slidably holding said valve and stop in position.

7. A relief valve mechanism comprising a valve plate, a port through said plate, a valve seat adjacent said port, a resilient 75 plate valve adapted to rest on and close said port, a hole through each end of said valve, a resilient plate stop, a hole through each end of said stop, said valve holes and stop holes registering, means for spacing the stop from the valve, a hole through said spacing means adapted to register with a hole in the valve and stop, and means extending through said holes for snugly but slidably 80 holding said valve, spacer and stop in position.

8. A relief valve mechanism comprising a valve plate, a port through said plate, a valve seat adjacent said port, a resilient 85 plate valve adapted to rest on and close said port, an opening through said valve at each end thereof, a resilient plate stop, an opening through said stop at each end thereof, the openings through said valve and stop adapted to register, means for spacing the stop from the valve at each end thereof, a washer for each end of the valve and stop, said washer having a substantially axial prolongation adapted to fit loosely into the openings of the valve and stop, a screw to hold said washer to said valve plate, said prolongation on said washer of such length as when said screw is screwed down to hold said valve and stop snugly but longitudinally 90 slidably in position.

In testimony whereof we have hereunto set our hands.

EDWARD R. DE LUIZ.
HARRY L. MITCHELL.
